US00D787557S

(12) **United States Design Patent** (10) **Patent No.:** **US D787,557 S**
(45) **Date of Patent:** **** May 23, 2017**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Eunji Ahn**, Seoul (KR); **Joonho Ok**,
Seoul (KR)

(73) Assignee: **SAMSUNG ELECTRONICS CO.,
LTD.**, Gyeonggi-Do (KR)

(**) Term: **15 Years**

(21) Appl. No.: **29/549,565**

(22) Filed: **Dec. 22, 2015**

(30) **Foreign Application Priority Data**

Sep. 2, 2015 (KR) 30-2015-0044191

(51) **LOC (10) Cl.** **14-04**

(52) **U.S. Cl.**

USPC **D14/495**

(58) **Field of Classification Search**

USPC D14/485-495

CPC ... G06F 3/0481; G06F 3/0482; G06F 3/04842

(57) **CLAIM**

We claim, the ornamental design for a display screen or portion thereof with graphical user interface, as shown and described.

DESCRIPTION

The FIGURE is a front view of a display screen or portion thereof with graphical user interface showing our new design.

The broken lines showing the display screen or portion thereof are included for the purpose of illustrating environmental structure and form no part of the claimed design.

1 Claim, 1 Drawing Sheet
